TELEGRAPHIC PRINTING SYSTEM AND
METHOD

Joseph J. Ackell, Bellaire, and Herbert L. Paulding, Fort Washington, N. Y., assignors, by
mesne assignments, to Dow Jones & Company,
Inc., Wilmington, Del., a corporation of Delaware

Application December 22, 1945, Serial No. 636,588

12 Claims. (Cl. 178-4)

1

This invention relates to an improved system for transmitting, receiving and interpreting telegraphic signals by which messages may be printed on suitable apparatus under remote control. It has particular reference to the control of telegraphic page printers although certain features of the invention are applicable to tape printers.

A primary object of the invention has been to speed up the operation of telegraphic printing systems in which the selection of a character to be printed, or of some other function of the printer, is effected by the step-by-step rotation of a printing wheel. Toward this end the invention contemplates the step-by-step advance of the printing wheel two characters at a time, provision being made for the selection of the desired one of two adjacent characters on the wheel.

While the present invention is adaptable for a wide variety of uses it is particularly intended for use in connection with a system in which signals in the form of electrical pulses are sent out over a plurality of transmission lines to a large number of printing units at outlying points which are, for example, in the hands of subscribers, at those points, to the news or stock quotation service, or the like, with which the system is identified. The transmitted signal or series of pulses may, for example, be sent out by a transmitter which is under control of a punched tape, this tape having been punched in accordance with the characters to be printed, or other functions to be performed, at the outlying points. In such a system the control tape may be perforated by means of manually controlled punching devices. Several operators may be engaged in this work and then a single transmitter may be used to send out the signals determined by the several tapes. In transmitting a message the appropriate series of pulses will be sent out over the lines to cause the printing wheels to rotate step by step to the successively selected positions.

According to the present invention the signals or pulses which cause the step-by-step rotation of the printing wheels are alternately positive and negative pulses. The printing operation is controlled by a signal of somewhat greater duration than the regular pulsing signals. In one embodiment of the invention the printing is controlled by an open signal of predetermined duration and a distinction is drawn between two different types of printing operation according to the length of this open signal. Thus the type

2

wheel is rotated step by step two character spaces at a time, by alternate positive and negative pulses, and then if one of two adjacent characters is to be printed a relatively short open signal will be transmitted to cause the printing while if the other of the two characters is to be printed an open signal of longer duration will be sent and this will bring about a slight rotation of the printing wheel, to the extent of one character, before the platen is operated to effect printing.

It is thus a broad feature of the invention to provide a commutator and suitable electrical circuits operable in conjunction therewith to transmit current signals for the operation of escapement mechanism to effect a partial selection of a character and to transmit a signal of different character to complete the selection.

A special feature of the invention, which enables the use of the positive, negative and open signals of different duration for controlling the various functions of the printer, is the use of a rectifier in combination with a relay to differentiate between the various signals.

Another feature of the invention is the provision of suitable circuits and devices by which the remote printer may be set into operation by the simple sending out of a current signal and the printer may be thrown out of operation by the opening of the transmitting circuit for a predetermined length of time.

Still another feature of the invention is the utilization of open signals of varying duration to perform a wide variety of different functions. Thus, in the preferred embodiment of the invention relatively short open signals of different duration will complete the selection of the character to be printed. An open signal of somewhat longer duration will cause the ringing of a bell in the printer and an open signal of still longer duration will cause the printer to be thrown out of operation.

A further feature of the invention in its preferred form is the arrangement of the characters on the printing wheel in such a way that those most frequently used are arranged alternately around the wheel and in positions requiring the least to be done in effecting a printing operation. Thus, in the one embodiment the arrangement is such that the characters most frequently used are printed without the necessity of a one-step backward turn of the wheel. The remaining characters are interspersed with these and require the turn-back operation. In so far as compatible with the foregoing the characters

are arranged with regard to frequency of occurrence in sequences.

In connection with the foregoing it is a further feature of the invention to provide means at the transmitter for adapting the conventional five-hole punched tape, with its customary relation between the tape openings and the characters selected, to the selection of the characters in their new arrangement around the printing wheel.

Other objects, features and advantages of the invention will appear from a detailed description of several illustrative forms of the invention which will now be given in conjunction with the accompanying drawings, in which:

Figs. 1 and 2 in combination, with Fig. 1 above Fig. 2, disclose schematically devices at both the transmitting and receiving ends of a printing telegraph system embodying certain features of the invention;

Figs. 3a and 3b placed side by side with Fig. 3a at the left of Fig. 3b, disclose schematically the circuits involved in a more complicated modified form of transmitter embodying the invention;

Figs. 4a and 4b are current flow diagrams indicating the character and duration of the current flow through the coil of the escapement magnet of the system disclosed in Figs. 1 and 2 under certain assumed conditions;

Fig. 5 is a similar current flow diagram showing the character and duration of the current flowing through the signal transmitting lines of the system disclosed in Figs. 3a and 3b; and

Fig. 6 is a diagrammatic view of the circuits in a printer adapted to be controlled by the transmission system illustrated in Figs. 3a and 3b.

Turning now to Fig. 2, the system illustrated is of a relatively simple type adapted for manual control by keys 10 cooperating with helically arranged pins or stops 11 on a drum 12 which is arranged to be driven in a counterclockwise direction, as indicated by the arrow 13. A friction clutch is provided in the drive between a motor (not shown) and the drum 12, to permit slippage of the drive whenever the drum is arrested by a depressed key.

The parts are illustrated in Figs. 1 and 2 in the position they will assume after the letter V has been printed. Assuming now that it is desired to print the letter M, the M key will be depressed and this will automatically release the previously depressed V key, in a manner known in the art. The cylinder 12 will begin to turn and will rotate until stopped by the cooperation of the selected pin 11 with the M key. In the rotation of the drum 12, a commutator 14, which is connected to turn with the drum, will rotate to carry several of its sections past a group of brushes 15, 16, and 17. On the first step of movement from V to H a current will pass between the brushes 16 and 17. This current may be traced from the positive side of a generator 18 through brush 17, through the commutator segment in line with the letter H, thence through brush 16, partly through a line 19 to and through a relay 20, and then back through a line 21 to the negative side of the generator 18. For a reason to be explained hereinafter, the relay 20 is of a slow acting type and will not operate to pull-up on its armature 20a in response to the brief flow of current just mentioned, assuming that the commutator continues to rotate until an insulating section is brought opposite the brushes and thus breaks the flow

of current just described. Another branch of the circuit through the brushes 16 and 17, as described above, will pass through a line 22, through an armature 23 of a relay 24, thence through a line 25 to and through the coil of a pulsing magnet 26 (Fig. 1) which operates an escapement 27 associated with an escapement wheel 28. The latter is carried by a printer shaft 29 on which is mounted a type wheel 29a whose position corresponds at all times with the position of the commutator 14. From the pulsing magnet 26 the circuit passes through a line 30 to a rectifier 31 in which the current is directed as indicated by the arrow 32 to the point 33, thence through the coil of a relay 34, back through a line 35, and through a branch 36 of the rectifier to a line 37 from which the current returns to the negative side of the generator. Flow of the current through this second branch 20 of the circuit not only serves to pulse the escapement 27, 28 one step, but also serves to pull-up on an armature 38, because of the passage of the current through coil 34. As a result of this action on armature 38, current from a source 39 25 will flow through a line 40 to and through the coils of a printing magnet 41 and back through a line 42 and armature 38 to the source. Operation of the printing magnet will release the printing shaft 43 and permit it to be rotated 30 slightly until a projection 44 on an escapement disc is brought against the lower tooth of a printing-control escapement pawl 45. As the shaft 43 turns in the manner indicated, driven through a suitable friction clutch, by a motor 35 not shown, in a manner well known, a cam disc 46 has its high portion carried away from the end 47 of a pawl 48 and thus permits this pawl to rock in a clockwise direction to retract a pawl 49 in preparation for a possible one step return 40 movement of the shaft 29, in a manner to be explained hereinafter.

Simultaneously with the energization of the printing magnet 41, current from the source 39 will also flow through a magnet coil 50 thus 45 pulling-up on an armature 51 and rocking the pawl 49 in a counterclockwise direction to carry its active tooth 52 out of engagement with a ratchet wheel 53 on the printing wheel shaft 29. Magnet 50 is operative in this manner 50 throughout the pulsing operations of the magnet 26. This is necessary to enable the step-by-step movement of the printing wheel shaft in response to the pulsing operations of the escapement 27, 28.

55 It should be noted at this point that so long as the commutator 14 is rotating from one position to the next, current will flow through the relay 34 in the manner explained to pull-up on the armature 38 and permit current from the 60 source 39 to pass through both the printing magnet 41 and the magnet 50, thus maintaining the parts in the position just described.

Returning now to the commutator, as the latter continues to rotate and carries the next position, 65 designated K, in line with the brushes, no current will flow through the circuits including these brushes and, therefore, no pulsing operation will be imparted to the escapement 26. The pawl 27 will remain in the position to which it was last 70 shifted. Since the commutator continues its rotation at this time the open circuit created is very brief. For this purpose the insulating sections between the successive conducting sections of the commutator are very short, circumferentially. The interruption of the current flowing 75

through the relay 34 will not be of sufficient duration to release the armature 33 and hence current from the source 39 will continue to flow through the printing magnet 41 and the magnet 50.

Upon the continued rotation of the commutator the part opposite letter L will be brought in line with the brushes and current will flow between the brushes 15 and 16. This current will flow from the positive side of the generator 18a through the line 37, through the rectifier in a clockwise direction to the point 33, through the relay 34, back through the line 35 to the rectifier, up to the point 54 in the rectifier, through the line 36, thence through the pulsing coil of the escapement 26 in the reverse direction from the preceding pulse, back through the line 25, armature 23, line 22, brush 16, brush 15, and line 55 to the negative side of the generator 18a. The reverse flow of the current through the coil 26 in the manner explained, will cause the escapement pawl 27 to rock to the opposite side, thus permitting the escapement wheel 28 and shaft 29 to rotate through $1/20$ of a revolution in the illustrative system, in which wheel 28 has ten teeth. It should be noted, furthermore, that due to the action of the rectifier 31 the current flowing through the relay 34 is always in the same direction regardless of the fact that the current is reversed or alternated in its flow through the lines 25, 30 and 31.

As the commutator 14 now continues to rotate, the insulating section opposite the dollar sign is brought in line with the brushes and a temporary interruption of the current from the generators 18 and 18a is encountered. However, the situation is the same as explained above in connection with the insulating section K. Now as the commutator continues until the segment M is brought in line with the brushes, current will flow between the brushes 16 and 17 in the same manner as explained in connection with section H of the commutator so that current will flow through the coil 26 of the escapement from the line 25 to the line 30, thereby shifting the escapement pawl 27 to the other side and permitting another step of rotation of the escapement wheel 28. Since we have assumed that the M key has been depressed, the cylinder 12 will now be arrested with the commutator segment M in line with the brushes, thus continuing the circuit through the brushes 16, 17 for a prolonged interval. This interval will be sufficient to bring about operation of the slow relay 26 so that the armature 28a of the latter is drawn up, thus permitting the flow of current from the positive side 56 of a current source through the relay 24, through a conductor 57 to contact 58, thence through armature 28a to and through a condenser 59 down to the negative side 60 of the current source. This current, however, will have a sufficient amperage to retain the armature 23 toward the left for a brief interval, i. e., a time sufficient to charge the condenser 59 to a predetermined extent. During this brief interval of current flow the relay 24 will have been energized and the armature 23 will have been pulled away from the contact 61 so that the current flowing through the line 25 to the pulsing coil 26 and also through the relay 34 will be temporarily interrupted. The interruption of flow through the coil 26 will simply serve to leave the escapement pawl 27 in its last set position. Interruption of current flow through relay 34 will permit the armature 33 to be released and will thus

interrupt the flow of current from the source 39 through the printing magnet 41 and through the magnet 50. This interruption of current will, however, be relatively brief since the condenser 59 will be charged rather quickly and the current then permitted to flow through the circuit from 56 to 60 will be too small to hold armature 23. The interruption, however, is sufficient to permit the spring 62 associated with the printer escapement pawl 45 to rock the latter in a clockwise direction, thus releasing the projection 44 from the lower tooth of the pawl and permitting about 140° of revolution of the shaft 43, until projection 44 strikes the upper tooth of the pawl. During this revolution of the shaft 43 various things identified with the printing operation are performed. Firstly, the cam 46 will act upon the pawl or lever 48 to rock the latter counterclockwise and carry the pawl 49 longitudinally toward the left in Fig. 1. Magnet 50, however, will be energized at the time the pawl 49 is thus shifted because of the briefness of the interval of de-energization determined by the condenser 59. Therefore, the pawl 49 will be ineffective and will not rotate the ratchet wheel 53 and the printing wheel 29a will remain in the position determined by the escapement 27, 28. Rotation of the shaft 43 will also cause a cam 64 to operate a printing lever 65 and thus carry a platen 66 against the type of the wheel 29a which has been selected. This will, in the assumed case, be the letter M. It will be understood, of course, that paper will be interposed between the platen and the printing wheel at this time and it will also be understood that the wheel is suitably inked in the course of its rotation, as by contact with an inked felt roller.

The printing wheel 29a is preferably shiftable axially of the shaft 29. For this purpose it is mounted upon a carriage (not shown) which may be similar to that shown in the Landfeare Patent No. 765,978 granted July 26, 1904, and adapted to be given a step-by-step movement across the page upon which the printing is being done. Upon completion of the printing of a line across the page, the carriage may be automatically restored to the opposite side and the operation repeated. In the simple form of circuit illustrated in Figs. 1 and 2 no control is shown for the operation of the carriage either step-by-step or in its return movement toward the opposite side. However, it will be understood that any suitable arrangement may be employed for this purpose, such as the arrangements described hereinafter in connection with the more complicated circuits illustrated in Figs. 3 and 6.

Fig. 4a illustrates schematically the flow of current from the generators 18 and 18a through the pulsing coil 26 and the rectifier 31 as well as through the parallel circuit of the relay 20. The line in this diagram indicates the control over the current from the generators 18 and 18a exercised by the commutator 14 in cooperation with the brushes 15, 16, and 17. In moving from the position V to and beyond position H a positive current of a duration indicated by the length of the section 67 will flow through the pulsing coil 26 and through the relay 20. The duration of this current, however, is not long enough to operate the relay 20, which as indicated above is a slow acting relay. In passing from H to K the current will be interrupted through the pulsing coil, the rectifier, and the relay 20, as the brush 16 strikes the insulating section at K, but this interruption is for a considerably briefer period than

the positive current flow indicated at H. When the segment L of the commutator reaches the brushes, a negative current will flow through the pulsing coil and through the relay 20, thus rocking the escapement pawl 27 in the opposite direction from that in which it was rocked by the current flowing at position H. Another brief interruption in the current occurs at the dollar sign position as the brush 16 passes over the insulating segment at this point and this is followed by a positive flow of current when the segment M is brought in line with the brushes. As schematically indicated by the line in Fig. 4a, the commutator predetermines a long period of positive current flow through the pulsing coil circuit as the drum is now brought to rest by the M key but due to the operation of the relays 20 and 24 at this time, the actual current flow through the pulsing coil 26 is modified to correspond with that indicated by the line in Fig. 4b. Thus the temporary opening of the circuit between armature 23 and contact 61, due to the attraction of armature 21a and the resulting flow of current through relay 24 and condenser 59, will produce the interruption indicated at 68 in Fig. 4b. As soon as armature 23 is released, however, the positive pulse will be restored, as indicated by the section 69 of the current flow line.

Let us assume now that the next character to be printed is the numeral 3. This, as will be seen, is the next position on the commutator to the letter M in which the parts are assumed to have been arrested. It will also be noted that this is opposite an insulating section so that depression of the 3 key will stop the drum 12 with an insulating section in engagement with the brush 16. Since the effect of moving from the conducting sector at M, which bridges the two brushes 16 and 17 to the insulating section at 3, is simply to interrupt the flow of current through the pulsing magnet 26, the escapement pawl 27 will remain in its last set position and, therefore, the shaft 29 and printing wheel 29a will remain as last set. It should be noted, moreover, that the interruption of the flow of current through the relay 20 at this time serves to release the armature 20a and thus breaks the circuit from 56 to 60 through the condenser 59 and permits this condenser to be discharged through the resistor 70. It may be noted at this point that the release of the armature 20a and the consequent discharge of the condenser 59 would have taken place even though no prolonged interruption of current flow had taken place at this particular instance. That is, if the commutator were permitted to rotate for some distance, so that a pulsing current would be permitted to flow through the relay 20, this would, nevertheless, release the armature 20a and thus condition the condenser 59 for the next printing operation. Any reversal of flow of the current through the relay 20 will bring about such release of the armature.

It will be noted by reference to the diagram of Fig. 4b that at the conclusion of the printing operation for the letter M current will have been flowing through the relay 34, whereas upon the operation of the 3 key and the turning of the cylinder 12 to this new position, the current flow through the relay 34 will be interrupted, this interruption being relatively long. The effect of this is to release the armature 38 and thus break the circuit through the print magnet 41 and the magnet 50 throughout the long interruption.

Upon de-energization of the print magnet 41, spring 62 will rock the pawl 45 clockwise to release its lower tooth from the then engaged projection 44 and will permit the shaft 43 to rotate until this projection 44 is arrested by the upper tooth on the pawl. As in the previous printing operation, the cam 46 will operate the lever 48, rocking it in a counterclockwise direction to carry the pawl 49 toward the left and since, at this time, the magnet 50 will be de-energized the spring 71 will draw the armature 51 downwardly and rock the pawl 49 into engagement with the ratchet 53. The longitudinal movement of the pawl 49 will, therefore, turn the ratchet, and hence the shaft 29, through a step in a backward direction. This step is $\frac{1}{40}$ of a revolution of the shaft in the construction illustrated. It is only one-half the movement given the shaft upon each operation of the escapement. In this connection it should be noted that ratchet 53 has 20 teeth, when ratchet 28 has 10 teeth. Thus at the time the cam 64 operates upon the printing lever 65 to effect the printing operation, the wheel 29a will have been turned a step back from the position which it assumed upon the printing of the letter M. It will be noted, in this connection, that the arrangement of the characters on the printing wheel 29a differs from the arrangement of the corresponding positions on the commutator 14. Thus, whereas the figure 3 follows the letter M on the commutator, it must precede the letter M on the printing wheel.

Assuming now that the next character to be printed is the letter E, depression of the E key 35 will permit the commutator to rotate one more step and will carry the conducting segment opposite E (Fig. 2) into line with the brushes to complete a circuit through the brushes 15 and 16. This causes a current to flow from the positive side of the generator 18a through line 37, through rectifier 31, relay 34, and line 30 to the pulsing magnet 26, then back through the line 25, armature 23, line 22, brush 16, contact segment E, brush 15, and line 55 to the negative side of the generator. The current in passing through the pulsing coil will cause the escapement pawl 27 to shift to the opposite side and permit another step of movement of the ratchet 28 and hence the printing wheel. It should be observed in this connection that each movement of the printing wheel, permitted by each step of movement of the ratchet 28, serves to carry two characters past the printing point. Thus a 10 toothed ratchet 28 may be stopped in any of 20 different positions by the pawl 27 and the printing wheel 63 may have as many as 40 characters or spaces around its periphery.

The current in flowing through the relay 34, as just explained, will serve to energize the print magnet 41 and the magnet 50, the latter being necessary to permit the rotation of the shaft 29 through the one step indicated. By energizing the print magnet 41, the shaft 43 is released for a partial movement of about 40° until the next tooth 44 engages the lower tooth on the pawl 45. This, as previously explained, is sufficient to cause rocking of the lever 48 in a clockwise direction, thus retracting the pawl 49 and making it ready for the next operation in the event that it is necessary to turn the printing wheel shaft 29 a half step backwardly in the manner explained. However, in printing the letter E the pawl 49 will not be rendered effective since the interruption of flow through the relay 34 will be of the shorter type predetermined by the con-

denser 59. This fact is shown by the section 12 of the current flow line in Fig. 4b, this section being similar to the section designated 69.

The foregoing simple system serves to illustrate the principle of utilizing positive and negative pulses through the escapement coil 26 to bring about step by step movement of the type wheel and of utilizing a neutral signal, or an interruption of current, to bring about a printing operation which may be of either of two types depending upon the length of the interruption. A short interruption will cause printing of the character selected by the escapement 27, 28, whereas a long interruption will bring about the printing of the character just in advance of the one selected by the escapement 27, 28. This is accomplished by the operation of the pawl 49, which turns the printer wheel backwardly a half step upon a long interruption.

Figs. 3a and 3b, placed side by side, illustrate schematically a system of circuits forming part of a transmitter generally similar to that disclosed in the Ackell and Paulding Patent No. 2,017,037, granted October 15, 1935. The system disclosed in Figs. 3a and 3b, however, is adapted for use with the conventional five hole type of tape now commonly employed in the control of telegraph printers. Briefly, the arrangement is such that the message to be transmitted is set up by an operator on the keys of a punch controlling machine which serves to perforate a tape in any number of the five possible positions for each key depressed. This provides for a possibility of 32 commutations and permutations. The tape that is so punched replaces the keys of the system disclosed in Fig. 2, while a tape analyzing device, including a series of 5 pins capable of cooperating with the various holes in the punched tape and various relays and circuits controlled by switches, operated in response to the action of the pins, and a commutator structure replace the pin cylinder 12 and the commutator 14.

As in the Fig. 2 embodiment, the signals sent out from the transmitter of Fig. 3 are of three different types, i. e., positive, negative, and open. The positive and negative signals are utilized to bring about the step by step pulsing operations of the printers at the outlying points, while the open signals are used for any one of five different purposes. A short open signal will bring about a printing operation at the distant machines of a kind in which a character on the type wheel that is brought to the printing position by the normal pulsing operation of the escapement mechanism is printed. A longer open signal of say twice the duration of the short signal mentioned above, will bring about a printing operation in which the type wheel is turned a half step or character space backward from the position predetermined by the pulsing of the escapement mechanism, before the printing takes place. A still longer open signal, of say 3 or 4 times the duration of the second mentioned long open printing signal, will bring about the return of the carriages of the various outlying printers. A still longer open signal, of say about five times the duration of the carriage return signal, will bring about the ringing of a bell at each of the printers. Finally, an open signal of indefinite duration, i. e., of 4 or 5 minutes or more, will bring about the cutting off of power to all of the outlying printers.

The printers which are to be controlled by the signals sent out through the operation of the

transmitter illustrated in Figs. 3a and 3b, may suitably be of the same construction as is diagrammatically illustrated in Fig. 1. So also, as indicated by the foregoing, the manner of control of this printer is substantially the same as described in connection with Figs. 1 and 2. There are, however, a few specific differences. For example, the Fig. 3 system has the ability to repeat the same character without causing any change in the position of the printing wheels of the printers, other than that which might be necessitated as a turnback in the printing operation. In the operation of the Figs. 1 and 2 construction, this was not possible since it was necessary on each operation of the transmitter to operate a different key from that depressed on the preceding operation in order to release the latter and initiate the new cycle. This would necessarily bring about a turning of the cylinder 12 through at least one step. Even in the Fig. 1 system, however, this need not result in the pulsing of the escapement but might result merely in a turnback operation of the printing wheel for the new printing operation when the preceding printing operation did not involve such a turnback.

Another distinction between the systems of Figs. 1 and 3 is that in the Fig. 1 system the duration of the printing period is predetermined by the time interval allowed by the operator in depressing successive controlling keys 10. The operator is required to delay sufficiently between the depression of successive keys to afford time for the necessary partial rotation of the control cylinder 12 and the subsequent operation of the printing devices. In the Fig. 3 system, on the other hand, a special timing means similar to that disclosed in the Ackell and Paulding patent above mentioned, is provided. This timing means, which comprises a driven shaft, is released for its timing cycle and for the performance of certain operations incident to the transmission of the desired printing signal upon the stopping of the main commutator brush arm which controls the transmission of the pulsing signals sent out to the various printers in the manner to be hereinafter described.

In the Fig. 3 system, it should also be observed that the arrangement of the characters on the printing wheel of the various printers is different from that heretofore considered desirable for printing telegraph purposes. The new arrangement is such that the characters which are most frequently encountered in the transmission of the desired messages are in those positions on the printing wheel which do not require the turning back of the printing wheel to effect printing therefrom. Those characters which are encountered less frequently in the transmission of messages are placed in the intermediate positions which require a turnback of the printing wheel to effect printing therefrom. The particular relative positions of the characters in each of the two categories above mentioned is determined in accordance with the principle heretofore employed in the location of the characters about a printing telegraph wheel, i. e., in accordance with the frequency of occurrence of various combinations of characters. In conformity with the foregoing principles, the characters in the new construction are arranged about the printing wheels in the following sequence: those characters located in the positions not requiring a turnback of the printing wheel to effect printing therefrom are in the order of Space, B, T, P, C, H, L, M,

E, A, U, I, O, N, G, R, F, D, Y, and S, while those characters requiring a turnback of the printing wheel to effect printing therefrom are arranged in the order Cr, Q, J, W, V, K, \$, 3, 5, 7, 9, X, &, Z, -, 2, 4, 6, 8, and period. These latter characters are interspersed between those of the first series and in each instance they precede those of the first series. Thus Cr is in advance of space, Q is in advance of E, etc.

In considering the schematic showing of Figure 3 it should be understood that the transmitter resembles, in a general way, that illustrated in the above mentioned Ackell and Paulding patent. The new construction differs, however, in detail from that of the patent chiefly because the controlling tape is of the 5 hole, rather than the 8 hole, type. This necessitates specific differences in the form and arrangement of the commutator, collector rings, and cooperating brushes. There are but two annularly disposed series of commutator segments, each having its own collector ring, one preferably continuous and the other subdivided. The brushes cooperating with the commutator segments and the collector rings are carried by two arms which in themselves are conductors but which are mounted in an insulating block secured to the rotating shaft of the transmitter.

Referring now to Figs. 3a and 3b, the rectangular block designated 101 at the top of the figures represents diagrammatically the collector ring associated with the pulsing commutator which is in turn represented diagrammatically by the series of equally spaced and equally long blocks designated 102. In the actual construction of the transmitter the collector ring 101 is preferably provided as the innermost ring, while the commutator segments 103 are preferably provided as the adjacent ring of the commutator assembly. The next ring of the commutator assembly is a divided collector ring having a number of small segments of equal size and several larger segments of different lengths. These, collectively, are diagrammatically illustrated by the blocks 103. The sections, or segments, are interconnected in accordance with 3 groupings as will be explained more fully hereinafter. One of these groups of segments is identified with letters, another group is identified with figures, and a third group is identified with both letters and figures. The reason for this third group is that certain characters are made to perform a double duty, i. e., one represents either the figure 1 or the letter I, and similarly O represents the figure 0 or the letter O. So, also, the carriage return and space positions of the divided collector ring of the commutator are classified as either figures or letters, so that they will be effective regardless of whether the figure shift or the letter shift is effective in accordance with the common practice in the 5 hole tape system.

The outer series of commutator segments in the preferred construction is identified with the various characters and special signals to be transmitted, and thus broadly corresponds with the key stops of the Figure 1 arrangement. These segments, which are diagrammatically represented by the blocks 104, are of equal size and, it will be noted, there are two such commutator segments for each of the segments 102. At the left end of the development of the commutator and collector ring members shown in Figures 3a and 3b there is graphically illustrated the pair of brush carrying arms 105 and 106, each arm carrying two brushes adapted to be shifted over the

commutator segments and collector ring sections with which they are associated and which they are intended to interconnect in the operation of the device in the manner to be described. The sectors or segments which are in vertical alignment will be simultaneously engaged. The two arms, it will be noted, are insulated with respect to each other as indicated at 107. In the actual construction, it will be understood, the arms are rotatably mounted about the axis of the commutator assembly, but for purposes of illustration they are indicated as though movably mounted longitudinally along the development of the commutator assembly. It should also be understood that the shaft carrying the brush arms 105 and 106 is arranged to be driven through a friction drive from any suitable source, such as a motor. Whenever desired the brush arms may be stopped while the friction driving means, which serves to rotate the shaft may continue. In the schematic showing a ratchet segment 108 is indicated, which should be understood to represent a complete ratchet in the actual mechanism. With this a pawl 109, which is spring urged into engagement with the teeth of the ratchet, cooperates to arrest the brush arms and their supporting shaft at desired intervals during the operation of the machine. As will be explained more fully hereinafter, the operation is such that the brush arms will be permitted to sweep over the commutator and collector sections until the commutator segment 104, which has been predetermined by a particular series of holes in the tape that controls the transmitter, has been reached by the corresponding brush. In fact the arrangement is such that the tooth of the pawl 109 cooperating with a tooth of the ratchet 108 will stop the indicated brush just as it reaches substantially the far or righthand end of the commutator segment. This allows the necessary time for the completion of the circuit which brings about the release of the pawl 109 and also time for the operation of the pawl by its spring 109a to effect the desired stoppage of the brush arms.

The arrangement by which the brush arms are brought to rest upon the desired commutator segments involves a plurality of relays 110, arranged in what may be described as a fan bank, and which are under control of the pins of the tape analyzer designated generally by the number 111. This is generally similar to the tape analyzer disclosed in the above mentioned Ackell and Paulding patent. There are, however, only 5 pins, 112, 113, 114, 115, and 116 in lieu of the 8 pins of the prior construction and the arrangement is such that any number of these pins from 0 to 5 may pass through the tape in a single operation. When the pin 112 passes through an opening in the tape, it serves to shift all of a group of relay arms 117 associated with the pin 112 toward the right, as they are shown in the diagram. A suitable frame or bar, not shown, may be provided to interconnect these arms for operation in unison. If at a particular position on the tape there is no hole for the pin 112, the arms 117 identified with the top row of the fan bank will be held to the left in engagement with the opposite contacts. Similarly the pin 113 when permitted to pass through an opening in the tape will cause all of a series of interconnected relay arms 118 to swing toward the right, whereas when no hole is in registry with this pin, these arms will be held in engagement with the opposite or lefthand contacts. In the same manner relay arms 119 are

associated with the pin 114, relay arms 120 are associated with the pin 115, and a relay arm 121 is associated with the pin 116. In the construction illustrated there are 16 relay arms 117, 8 relay arms 118, 4 relay arms 119, 2 relay arms 120, and a single relay arm 121. These provide for the 32 commutations and permutations permitted by the series of 5 holes in the tape.

As will appear more clearly hereinafter, the arrangement is such that for any particular setting of the analyzer pins only one circuit will be completed from the relay arm 121 to one of the 32 contacts engaged by the relay arms 117. All of the other 31 circuits will be broken at one point or another. Each of the 32 contact points associated with the relay arms 117 is connected with at least one of the commutator segments 104, with the exception of the contact 122 at the extreme lefthand end of the series, whose purpose will be described hereinafter. Many of the 32 contacts will be connected with two separate segments 104, while in some instances two separate contacts, of the 32 engaged by the relay arms 117, will be connected with a single commutator segment 104. There are 40 such commutator segments in the illustrative arrangement and these are connected with 31 of the contacts engaged by the arms 117. As will appear more clearly hereinafter, the selection of the desired one of the two commutator segments 104, predetermined by the setting of the pins 112, 113, 114, 115, and 116, is effected by the setting of a series of relays responsive to the conventional letter and figure shift signals predetermined by the tape. The arrangement in this regard is such that prior to the transmission of a particular character signal a shift signal may be set up by the tape analyzer and this will affect only the transmitter. It serves simply to shift a series of interconnected relay arms 123 either toward the right as shown or toward the left. These arms are associated with a polarized relay and will, therefore, remain in any position in which they are set until reset by another shift signal. In the layout illustrated, the righthand position of the arms 123 corresponds with the letter shift signal of the tape which is constituted by a series of 5 holes. The lefthand position of the relay arms 123 corresponds with the figure shift signal of the tape and is represented by holes aligned with the pins 112, 113, 115, and 116. Thus in a typical instance, assuming that the tape at a particular position is provided with holes in line with the pins 112, 115, and 116, a circuit will be completed through the relay fan bank 110 to the contact 124 identified with the characters W and 2. This contact is connected with both of the segments 125 and 126 of the commutator section 104. The determination as to which of these segments 125 and 126 is to be effective in stopping the brush arms 105 and 106 is made by the adjustment of the relay arms 123. If these are set in the position illustrated in Figure 3, because of the prior transmission of a letter shift signal, the segment 125 will be effective, whereas if the relay arms 123 had been shifted to the left, by the prior transmission of a figure shift signal, the segment 126 would have been effective.

When the brush arms 105 and 106 are brought to rest by the completion of a circuit through the selected one of the commutator segments 104, a print timing shaft 127 will be released for rotation through a half turn. This is accomplished by the disengagement of a pawl 128 from a tooth 129 on a disc 130 secured to the print timing shaft which is, in turn, driven through a frictional

connection with the driving motor of the transmitter, in a manner well known in the art. Two cams 131 and 132 carried by the printer timing shaft 127 serve to operate switch arms 133 and 134 respectively at appropriate points in the cycle to perform the functions to be hereinafter described.

In the movement of the brush arms 105 and 106 over the commutator segments, in the manner above explained, the brushes carried by the arm 105 will complete certain pulse transmitting circuits between the commutator segments 102 and the collector ring 101. Alternate ones of the commutator segments are connected with a line 135 which is, in turn, connected with the positive side of a current source 136, whereas the remaining commutator segments of the group 102 are connected through a line 137 with the negative side of a current source 138. It should be understood that these commutator segments, separated by the intervening insulating spaces on which the brush which sweeps over the segments 102 may come to rest, will function in the transmission of the pulsing segments to the distant printers in substantially the same manner as the commutator 14 of the Fig. 1 system. Certain differences between the functionings of the two systems, however, will be mentioned hereinafter. One difference which may be noted at this time is that the signals transmitted to the distant printers are not derived directly from the current sources 136 and 138, but are derived instead from current sources 139 and 140, which respond to the pulses of the current from the sources 136 and 138. While two generators in series are indicated as the source of the current which alternate flows in opposite directions, it will be understood that other means for accomplishing the same purpose may be substituted. A positive pulse emanating from the source 138 is passed through a rectifier 141, thence through a relay coil 142, back through another portion of the rectifier 141 and thence through a line 143 to and through a polarized relay 144 to the collector ring 101, thence through the brushes and brush arm 105 to one of the commutator segments 102 connected with the line 137. In energizing the relay 144 in this manner, its armature 145 will have been swung to the left to send out a new pulse over the series of transmission lines 146 to the distant printers. This signal will have come from the positive side of generator 139, through a line 147 to the transmission lines 146, thence back through the line 148, armatures 149 and 145 to the negative side of the power source 139. An advantage of this arrangement of dual power sources 136, 138 and 139, 140 is that only positive and negative pulses will be sent out over the lines 146 even though open pulses of brief duration may be produced in the circuits supplied by the power sources 136 and 138 as the brush sweeps over the gaps between the commutator segments 102.

Let us now trace certain specific circuits which are completed in the course of a series of operations of the apparatus such as those, for example, involved in transmitting the series of signals graphically illustrated in Fig. 5. We will assume that appropriate switches have been thrown to connect the apparatus schematically shown in Figs. 3a and 3b with one or more suitable sources of direct current which are graphically indicated. Let it also be assumed that the various outlying printers to be controlled by the apparatus of Figs. 3a and 3b have previously been set in operation,

this having been accomplished, as will be described hereinafter, by simply placing in operation, in any suitable way, the current sources 139 and 140. Let it also be assumed that prior to the transmission of the series of signals represented by Fig. 5, the last signal was that effecting printing of the letter P. In the course of the printing of the letter P a magnet 150 will have been energized, in a manner to be hereinafter more fully explained, to retract the pins of the analyzer 111 and the tape passing through the analyzer will have been shifted forwardly one step to position the next series of openings in the path of the pins. Also during this printing operation the magnet 150 will be de-energized and the pins will be permitted to rise wherever possible through the openings in the newly positioned portion of the tape. Under the assumed conditions a series of openings will be provided in line with the pins 112, 115, and 116 thereby predetermining the character W. This is, of course, on the assumption that the last shift signal transmitted was a letter shift. The movement of the specified pins through the openings in the tape will bring about the shifting toward their right-hand positions of all of the relay arms in the groups 117, 120, and 121, whereas the relay arms of groups 118 and 119 will remain in their left-hand positions. Tracing the current from the negative side 151 of the current source, it will be found to pass firstly through the coil 152 of a polarized relay which determines whether the system is to effect a character selecting operation or a printing operation. From this coil the current passes to and through the arm 121 of the first relay, thence through the line 153 to and through the righthand relay arm 120a, thence through the line 154 to and through the relay arm 119a, to and through the line 155, through the relay arm 118b to the line 156, and thence through relay arm 117d to the contact 124. The latter, as has previously been explained, is connected by suitable wiring to both of the commutator segments 125 and 126. When a circuit can be completed through the segment 125 by the bringing of the associated brush on the arm 106 across this segment, the balance of the circuit will be completed through the collecting ring section 157 and line 158 to and through the righthand armature 123a, and thence through the line 159 to the positive side 160 of the source of power.

Movement of the brush arms 105 and 106, to permit the completion of the circuit through the commutator segment 125 in the manner explained, is permitted by the withdrawal of the pawl 109 from the ratchet 108. This is accomplished in the following manner: Current from the positive side 161 of a current source flows through a coil 162 of a magnet capable of retracting the pawl 109, thence through a line 163 and through an armature 164 to the negative side 165 of the current source. Armature 164 will have been moved into engagement with the contact at the end of the line 163 by a current passing through a relay coil 166. Current for this purpose flows from the positive side 167 of a current source, thence through the coil 166, through a line 168, to and through an armature 169 of the polarized relay hereinbefore mentioned, this armature having been shifted toward the right prior to this, in a manner to be hereinafter described. Completion of the circuit will be through line 170 to and through the arm 133 to the negative side 171 of the current source. Arm 75

133 it will be noted, is held against the contact at the lower end of line 170 by cam projection 172 on the cam 131 secured to the print timing shaft 127. Release of the ratchet 108 in the manner indicated, will, under the assumed conditions, allow but a single step of movement of the arm 106 to carry its brush from the previously engaged segment P to the segment W, designated 125, which, as previously indicated, will complete the circuit through the relay fan bank. Completion of the circuit through the fan bank in this manner energizes the coil 152 of the polarized relay thereby pulling the armature 169 toward the left into the position indicated in Fig. 3. This breaks the circuit previously traced through the armature 169 and the relay coil 166 and releases the armature 164 to break the circuit through the magnet 162 and thus releases the pawl 109 for re-engagement with the ratchet 108. The mechanism just described will respond with sufficient rapidity to insure stoppage of the brush on the W segment designated 125.

Shifting of the armature 169 to the left in the manner indicated completes a circuit from the negative side 171 of the current source through the line 170, through the armature 169, through a line 173, a branch line 174, to and through a relay armature 175, and thence through a line 176 and a branch line 177 to and through a coil 178 of another relay, thence through a further relay coil 179 and a line 180 to and through an armature 181 to the positive side 182 of the current source. In passing through the relay coil 178 the current will pull-up on the armature 183, thereby completing a circuit from the positive side 184 of a current source through the armature 183, a line 185, and a magnet coil 186 to the negative side 187 of the current source. Magnet coil 186 will attract the pawl 128 and thereby disengage it from the projection 129 on the stop disc 130 secured to the print timing shaft 127. A half rotation of this shaft will thus be permitted. Passage of the current through the coil 179, as explained above, will have served to throw to the left, as shown, an armature 188 of a polarized relay to complete a circuit from the negative side 189 of a current source to and through a line 190, then to and through coil 150 to the positive side 191 of the current source. Coil 150, as has previously been explained, serves the purpose of retracting the feeler pins of the analyzer and it serves also to operate a ratchet which advances the tape to the next position, in any convenient manner, not shown.

Upon the commencement of the rotation of the shaft 127 the projection 172 will be rather quickly carried away from the end of the arm 133 and will permit the latter to be drawn by the spring connected therewith toward the right. This serves to break the circuit which was previously completed through the arm 133, line 170, armature 169, line 173 down to and through the coil 178, etc. in the manner previously explained. Breaking of the circuit to the coil 178 serves also to break the circuit through the coil 186 and thus releases the pawl 128 to arrest the printing shaft as the stop 129a is brought against the tooth of the pawl. Simultaneously with the breaking of the circuit explained above, a new circuit is completed from the negative side 171 of the power source through the arm 133, thence through a line 192, through a coil 193 of the polarized relay acting upon the armature 188, thence through a coil 194 of the polarized relay acting upon the armature 169, thence through a coil 195 of a

further relay, through a line 196 and the arm 134 to the positive side 197 of the current source. In passing through the coils 193 and 194 it will be understood that the armatures 188 and 169 will be shifted toward the right and will so remain until the coils 179 and 152, respectively, are energized again.

As has previously been indicated, the shaft 127 serves the purpose of timing the printing operation of the system. So long as the shaft 127 is held stationary with the projection 172 operating upon the arm 133, the system may be said to be in the selecting condition and during this time only positive and negative pulses will be transmitted over the lines 146. On the other hand, when the shaft 127 begins to rotate to carry the projection 172 away from the end of the arm 133 an open signal of some duration, the length of which may vary according to the particular position at which the brushes are stopped at the end of the preceding selecting operation, is sent out over the lines 146. During this period, it is impossible to send a selecting signal over the lines because the circuit from 167 to 171 will be broken at the arm 133 and the pawl 109 can, therefore, not be retracted.

We shall now describe the production of the signals transmitted over the lines 146 incident to the movement of the brushes from the P segment to the W segment of the commutator 194 and incident to the succeeding printing operation. As the brush associated with the commutator ring 194 shifts from the P segment to the W segment, the brush associated with the commutator 192 shifts from the segment 198 to the insulating space 199 and remains there. In the course of this shift the circuit through the generator 138 will be broken, thereby de-energizing the coil 142 and releasing an armature 200. It should be mentioned here that coil 142 would not have been de-energized to release the armature 200 if the brush had simply passed over the insulation 199 and had not come to rest on it. Armature 200, prior to its release, completed a circuit from the positive side 201 of a power source through a relay coil 202, armature 200, line 203, armature 204, line 205, and an armature 206 to the negative side 207 of the power source. In passing through the coil 202 of the circuit just described, the power served to hold the armature 149 toward the left and thus kept the circuits through the lines 146 closed. Upon the release of the armature 200, however, in the manner explained, the circuit through the coil 202 will be broken and the armature 149 will be released to open the circuits through the lines 146.

In accordance with the system, as previously explained, the opening of the circuit at this time should be of the long printing duration and this is brought about as follows: It is determined by the time required for the shaft 127 to rotate sufficiently to carry a bump 208 on the cam disc 132 against the lower end of the arm 134 so as to shift the latter toward the left. This serves to close a circuit from the positive side 197 of the power source through a line 209 and a coil 210 of a polarized relay to the negative side 211 of a power source. The current in passing through the coil 210 serves to shift an armature 212 of the polarized relay toward the left, as shown in Fig. 3b and thus closes a circuit from the negative side 207 of the power source through a line 213 and the armature 212, thence through a line 214, through the coil 202 to the positive side 201 of the power source. This, it

will be seen, swings the armature 149 to the left again and terminates the open signal which has been transmitted over the lines 146.

Referring now to the diagram of Fig. 5, the section 215 of the current flow line represents the open circuit condition just described, during which the letter W will have been printed. As indicated by this diagram the shifting of the armature 149 toward the left in the manner explained at the completion of the printing cycle serves to restore the previously existing circuit which, in the example indicated, involved the transmission of a positive signal associated with the letter P. This is illustrated by the section 216 of the current flow line in Fig. 5. It will be appreciated that since this signal is of the same character as the last pulsing signal transmitted over the lines 146, it will not effect any movement of the escapement mechanisms of the various printers. This conditions the sending circuits 146 for the transmission of whatever signal it may be desired to transmit next. It may, if desired, be simply another open signal in the event that it should be desired to print the letter W again.

The arrangement is such that a maximum amount of time is permitted for the readjustment of the pins of the analyzer 111 and the relay fan bank armatures after they complete their function of determining the position in which the brush arms 105 and 106 are arrested. It should be noted in this connection that upon the swinging of the armature 169 toward the left, as the coil 152 is energized, while the bump 172 on cam disc 131 holds the arm 133 toward the left, a circuit will be completed through the coil 150 to retract the analyzer pins and shift the tape to the next position. This, as previously explained, is accomplished by the swinging of the armature 188 toward the left by the current passing through the coil 179. Release of the pins is accomplished in a relatively brief period after the commencement of the printing cycle by de-energizing the magnet 150 through the shifting of the arm 133 toward the right as the bump 172 is carried beyond the end of the arm 133. This movement of the arm 133 breaks the circuit from the source 171 through the armature 169, coil 179, etc. and thus allows the armature 188 to be swung toward the right upon the energization of the coil 193. This, as explained, results from the swinging of the arm 133 toward the right to complete the circuit from the negative side 171 to the positive side 197 of the current source.

It should be noted further that toward the end of the half revolution of the shaft 127, the projection 208 on the disc 132 acting upon the arm 134 will break the circuit from the source 197 to the negative side 171, thus de-energizing the relay coils 193, 194, and 195. The arms 169 and 188 will, however, remain toward the right until they are again shifted toward the left by the energization of the coils 152 and 179, respectively. It will be understood that at the completion of the printing cycle the parts associated directly with the shaft 127 will assume the position indicated in Figs. 3a and 3b.

Returning now to the assumed series of signals represented by Fig. 5, the new position of the tape aligned with the feeler pins 112 to 116, inclusive, will have perforations representing the letter O, these being opposite the pins 112 and 113. It is assumed, of course, that the transmitter is still operating on the letter shift side since no figure shift signal has been transmitted

subsequent to the printing of the W. Tracing the circuit that will now be completed through the relay fan bank 110 from the negative side 151 of the current source to the positive side 160, this will pass through the relay coil 152, armature 121, line 217, relay arm 120b, line 218, relay arm 119d, then relay arm 118h, then through relay arm 117o to the terminal 219 identified with the characters 0 and 9. This terminal is connected through the line 220 with the segment 221 of the commutator section 104 identified with the number 9. A branch line 222 extends from an intermediate point of the line 220 to the middle armature 123b of the series of three shift relays and from the latter to a segment 223 of the commutator 104 identified with the letter O. It will be noted that upon the completion of the previous printing cycle of the shaft 127 the circuit from the negative side 171 of the source of power will have been completed through the relay 166 to the positive side 167 of the current source and this, in turn, will have closed the circuit through the magnet 162 and will have released the brush arms for movement from the W position of the commutator 104 to the new position determined by the new setting of the feeler pins. Of the two sections 221 and 223 of the commutator 104 to which the circuit from the source 151 may be traced through the fan bank, only the section 223 is capable of completing the circuit to the positive side of the current source through the brush arm 106. This is because a segment 224 of the collector ring 103 is connected with a line 225 which connects with a line 226 extending toward the left to a contact 227 where the circuit is broken by the position of the armature 123a. Following the line 226 toward the right, it will be found to extend downwardly to and through a coil 228, thence upwardly through a coil 229 and then through a line 230 over to a contact 231 where a break in the circuit will again be encountered. The segment 223, on the other hand, is capable of completing a circuit through its related section 232 of the collector ring 103 by virtue of the connection of the latter through the line 233 with the positive side 160 of the current source. In shifting from the segment 125 of the commutator 104 to segment 223, in order to complete the circuit through the fan bank, the brush arm 105 will carry the brush associated with commutator 102 across a number of the segments of commutator 102 and across a number of insulating spaces between these segments, thereby sending out a succession of positive and negative pulses over the lines 146 in the manner hereinbefore explained. Thus in shifting from the insulating space 199 to the segment 234 a circuit will be completed from the positive side of the power source 136 through the line 135 to the segment 234, then through the brushes and brush arm to the collector ring 101, through the relay coil 144 and line 143 back through the rectifier 141 and relay 142 to the negative side of the power source 136. Passage of the current through the relay 142 at this time will serve to draw the armature 200 toward the left and thus close the circuit from the source 201 previously traced through armature 203, line 203, armatures 204 and 206 to the negative side 207 of the source of power, thus paralleling the circuit which has already been completed between points 201 and 207 through the line 214. In this connection it should be noted that the direction of flow through the coil 144 is opposite to that last flowing through this coil and, therefore, the armature 145 will be

swung toward the left. This will break the circuit from the power source 140 and complete a circuit from the power source 139 through the transmitting lines 146. A pulse of opposite sense to that last transmitted is sent over the lines, as illustrated by the section 235 of the current flow line on Fig. 5.

Now as the brush on arm 105 moves across the next insulating section 236 of commutator 102, there will be a temporary interruption in the flow of the current from either of the sources 136 and 138. This interruption, however, which stops the flow of current through the relay coil 142 is not of sufficient duration to permit the spring associated with armature 200 to draw the latter toward the right. This particular relay, it will be understood, responds slowly enough to permit this slight interruption without opening the circuit through the armature 200. As the brush on the arm 105 now moves to and across the segment 237 of the commutator 102, current will flow from the positive side of the current source 138 through the rectifier 141, coil 142, line 143, polarized relay 144, collector ring 101, segment 237, and line 137 back to the negative side of the current source 138. The direction of flow of this current through the coil 144 is opposite to that last flowing through this coil and will, therefore, shift the armature 145 toward the right again. This will cause a pulse of opposite sense to be sent out from the current source 140 over the lines 146. The same conditions as explained above will be repeated several times as the brush on arm 105 is carried across the successive sections 35 of commutator 102, and the insulating spaces between these sections, until the brush is finally brought to rest upon the section 238 of commutator 102. The series of pulses sent out over the lines 146 in this manner are graphically indicated in Fig. 5 up to the final pulse 239 which precedes the short open signal 240 indicated in this figure. We shall now explain how this short open signal is produced.

The brush on arm 106 having now reached the segment 223, identified with O in the manner explained, the circuit previously described through the fan bank 110 will have been completed. From the negative side 151 of the current source through the relay coil 152, and the other connections previously explained, to the positive side 160 of the current source. In flowing through the coil 152 this current will serve to draw the armature 169 again toward the left, thus breaking the current from source 171 to the positive side 167, thereby breaking the current through the coil 162 and releasing the pawl 108 for engagement with the ratchet 109 to stop the brush arms with one brush on segment 223 of commutator 104 and another brush on collector section 232.

Swinging of the arm 169 to the left serves to complete a circuit from the negative side 171 of a source of current, through line 170, armature 169, a part of line 173, a branch 241, armature 242 which will be at this time held toward the left by its spring, thence through line 243 and a relay coil 244 to the positive side 245 of the source of current. Passage of the current through the coil 244 in this manner serves to swing the arm 212 of the polarized relay toward the right thus breaking one of the two parallel circuits extending from the negative side 207 of the source of current up to the positive side 201 through coil 202. This is for the purpose of preparing the system for a subsequent opening of

the other of the parallel circuits so that coil 202 may be de-energized in the manner to be explained. Also the swinging of the arm 169 toward the left serves to complete the circuit from the negative side 171 of the source of current through line 170, armature 169, lines 173 and 174, armature 175, lines 176 and 177, coils 178 and 179, and line 180 to the positive side 182 of the current source. This current in flowing through coil 178 attracts armature 183 thereby completing a circuit through the coil 186 and withdrawing the detent 128 from the disc 130 on the print timing shaft 127. At the same time, the current flowing through coil 179 tends to shift the armature 183 to the lefthand position shown in Fig. 3. Swinging of the armature 188 toward the left, in this manner, will complete the circuit previously described from the negative side 189 of the power source through line 190 to the magnet 150 for withdrawing the feeler pins of the analyzer and shifting the tape to the next position. Rotation of the shaft 127 will promptly bring about the release of the arm 133 thereby breaking the circuit from the source 171 through the armature 169, etc., thereby releasing the armature 183 and breaking the circuit through coil 186 to permit the pawl 128 to return to its stopping position in engagement with the next tooth 129.

Simultaneously with the breaking of the circuit, as last mentioned, the shifting of the arm 133 upon the movement of the bump 172 beyond the lower end of this arm serves to close the circuit from the negative side 171 of the power source through the line 192, through coils 193, 194, and 195 to the positive side 197 of the power source. This current in passing through the coil 193 shifts the arm 188 to the right again thereby breaking the circuit through the magnet 150 and permitting the feeler pins to assume their new positions. Flow of the current through the coil 194 shifts the armature 169 to the right again, thus preparing the circuit through the coil 182 for a subsequent operation at the completion of the printing cycle. Flow of the current through the coil 195 serves to attract an armature 246 thus completing a circuit from the negative side 247 of a source of current through a condenser 248, thence through the armature 246 and through a line 249 to a coil 250 connected with the positive side 251 of the current source. This flow of current through the coil 250 will attract the armature 206 and thus break the circuit through the second of the two parallel circuits from the negative side 207 of the source of current up to and through the coil 202 to the positive side 201 of the source of current. Accordingly, the armature 149 will be released and an open signal will be sent out over the lines 146. The length of this open signal is determined by the condenser 248 since this will permit an adequate flow of current from the negative side 247 to the positive side 251 only so long as is required to charge the condenser to a predetermined extent, as explained in connection with the condenser 59 in Fig. 1. This time interval is represented by the section 240 of the current line indicated in Fig. 5. When the condenser 248 is charged to a predetermined extent and the current flow through the coil 250 is reduced, armature 206 is released to complete the circuit from the negative side 207 of the current source through armature 206, line 205, armature 204, line 203, armature 200, and coil 202 to the positive side 201 of the current source, thus attracting the armature 149 and transmitting over the lines 146 a pulse of

the same character as existed prior to the short open. This is indicated by the section 252 of the current line on Fig. 5. This condition continues until the next bump 208 on the cam 132 engages the arm 134 to shift it toward the left, thus breaking the circuit through the coil 195 and releasing the armature 246 to permit discharge of the condenser 248 through a resistance 253. Shifting of the arm 134 again establishes the circuit previously explained from the positive side 197 of a current source through line 209 and coil 210 so that the latter shifts the armature 212 toward the left again, thereby completing the other of the two parallel circuits between sides 207 and 201 of the current source. The conclusion of the printing operation in which the bump 208 passes beyond the arm 134, while the bump 172 of cam 131 engages the arm 133, is the same as previously described in connection with the printing of the letter W. As previously indicated, shifting of the arm 133 in this manner serves to complete a circuit through the coil 166 which, in turn, completes a circuit through the coil 162 to retract the pawl 109 and thus permits the movement of the brush carrying arms to the next position.

Assuming now that the new group of holes in the tape at the feeler pin position are identified with the carriage return signal, an opening will be provided in line merely with the pin 113. This will result in leaving all of the relay armatures of the 121, 120, 118, and 117 groups toward the left (Figs. 3a and 3b), whereas the group of relay armatures 118, including that designated 118h, will be shifted toward the right. Accordingly, as the brush arms 105 and 106 carry the brushes over the commutator segments, a circuit will be completed from the negative side of the source 151 through coil 152, armature 121, line 217, armature 126b, line 218, armature 119d, then armature 118h, and armature 117o to contact 254 which is connected through a line 255 with a coil 256 and then through a line 257 with the commutator segment 258 designated Cr in the commutator 104. The circuit is completed when the cooperating brush strikes this segment by the electrical connection through the brushes to the collector ring section 259 and thence through the line 233 to the positive side 169 of the source of current. It will be understood that as the brush arms shift to the new position from the O position in which they were last held, a series of alternate positive and negative pulses will be sent out over the lines 146 by the engagement of the brush on arm 105 with the successive segments of the commutator 102 from the position 233 to the end of the diagram in Fig. 3b and then to the segment 259 at the lefthand end of the showing of the commutator in Fig. 3a. Actually, of course, the commutator segments are arranged in a circle so that the transition from one end of the line to the other is the same as in shifting from one to the other of successive segments illustrated in the diagram. The brush arms are arrested when they reach the insulating section 261 of the commutator and hence an open signal is sent out over the lines 146. This, it will be understood, is due to the breaking of the circuit through rectifier 141 and coil 142, thereby releasing the armature 200 which, in turn, breaks the circuit through the coil 202 and releases the armature 149. It will be recalled in this connection that upon the completion of the circuit through the fan bank, as the brush

reaches the carriage return segment 258, a circuit will be completed from the negative side 171 of the current source through the armature 169, through the branch line 241, armature 242, line 243, and coil 244 to the positive side 245 of the current source. This serves to shift the armature 212 toward the right and thus opens one of the two parallel circuits through the coil 202. Such opening of one of the circuits occurs before the brush on arm 105 reaches the insulating space 261 so that as soon as the latter is reached and the armature 209 is shifted toward the right in the manner explained, both of the circuits through the coil 202 will be opened to transmit the open signal over the lines 146. The duration of this open signal will be considerably greater than an ordinary printing signal, even of the long type hereinabove described. This is due to the fact that the passage of the current through the coil 256, in the manner explained, serves to draw the armature 175 toward the left thus breaking the circuit which would normally be made through this armature to the coils 178, 179, etc. In lieu of passing through these coils, the current from the negative side of the current source 171 passes through armature 169 and line 173, then branch 174, armature 175, branch 262, relay coil 263, and thence through choke coil 264 to the positive side 265 of the source of current. The action of the choke coil 264 is such as to require a predetermined length of time to build up sufficient current to enable the relay coil 263 to shift its armature 266 toward the left. When this finally occurs the current, which in the ordinary printing operations passes through the armature 175 and line 176, in the manner previously explained, will now pass through the branch 267 to and through the armature 266 and thence through the line 177 and the balance of the circuit to the positive side 182 of the source of current. The pawl 128 will then be retracted, in the manner previously explained, to set the print timing shaft 127 into operation. Thus the duration of the open signal transmitted over the lines 146 will be determined by the length of time required to build up the necessary current through the choke coil 264 and then by the action of the timing shaft 127 in the same manner as for a printing operation of the long-open type. This extra long-open signal, indicated graphically by the portion 258 of the current flow line in Fig. 5, will operate through any suitable mechanism such as that disclosed in the patent to Landfear, No. 765,978, granted July 26, 1904, to release the carriages of the printers and permit them to be returned by their springs toward the left. Line spacing of the paper also takes place at this time. During this prolonged printing cycle the printing platen will be operated as in a normal printing operation but the type wheels of the printers, being in their carriage return positions, will have a blank space opposite the platen so that no printing will take place. It will be understood that, as in a normal printing operation, the relay armature 169 will be shifted toward the right in the course of rotation of the shaft 127 and will thus break the current to the relay coil 263 and the choke coil 264 so that the affected circuits will be restored to their normal conditions. Therefore, upon the completion of the half revolution of the shaft 127 the circuits controlled by the feeler pins of the analyzer 111 will be ready to function in the manner hereinafter explained.

It will also be understood that in the course of the half revolution of the shaft 127 the analyzer pins will have been retracted, the tape fed to its new position, and the analyzer pins released for their new setting. Assuming now that the new position on the tape is that representing a figure shift, holes will be provided in the tape in line with the pins 112, 113, 115, and 116. This will prevent the completion of a circuit through the armature 169, such as normally occurs to and through the line 168, coil 166, etc. and which normally retracts the pawl 109 associated with the brush arms 105 and 106. The reason for this is that, immediately upon the shifting of the relay armatures of the fan bank in response to the shifting of the indicated feeler pins, identified with the figure shift designation, a circuit will be completed from the negative side 151 of the current source through the armature 121, line 153, armature 120a, line 154, armature 119a, line 155, armature 118b, line 269, and armature 117c to the contact 270 identified with the figure shift. This contact is connected through a line 271 with a coil 272 and then through a line 273 with a coil 274 and on to the positive side 275 of the power source. This circuit will be completed before the shaft 127 completes its timing cycle for the preceding carriage return operation and, therefore, the armature 169 will have been shifted to the lefthand position by the coil 152 before the circuit which brings about the release of pawl 109 can have been completed.

It should be observed that upon the completion of the printing cycle for the carriage return, as represented by the section 268 of the current flow line in Fig. 5, the same type of signal will be sent out over the lines 146 as was last sent out. This, in the assumed series of signals, would be a negative pulse determined by the segment 260 of the commutator 102. It is indicated in Fig. 5 by the part 276 of the current flow line.

Now on completing the circuit through the coil 274, in the manner explained, the armature 242 will be drawn toward the right to complete a circuit from the positive side 275 of the current source through coil 274, thence through a branch line 277, through armature 242, line 241, and through the armature 169, line 170, and arm 133 to the negative side 171 of the source of current. This serves to hold the armature 242 shifted toward the right, even though the circuit through the fan bank may be opened. It should be noted in this connection that normally, upon the completion of the half cycle of the shaft 127, the circuit through the fan bank will be broken by the engagement of the bump 172 with the arm 133 serving in the manner previously explained to complete a circuit from the negative side 189 of the source of current through the retracting coil 150 for the feeler pins. The breaking of the circuit through the coil 274, which was predetermined by the previously shifted feeler pins identified with the figure shift designation, will not result in de-energizing this coil because the new circuit through the armature 242 will have been made. The purpose of this holding circuit is to prevent the transmission of an open signal over the lines 146 in response to the figure shift designation on the tape. Thus the current which would normally flow from the negative side 171 of the current source, through line 170, armature 169, line 241, armature 242, and line 243 to coil 244 and positive side 245 of the current source will, under the assumed con-

ditions, be broken at the armature 242 by the maintenance of this toward the right. This, therefore, prevents the coil 244 from shifting the armature 212 toward the right to break the circuit from the negative side 287 of the current source to the positive side 201 and thus prevents de-energization of the coil 202 so that no open signal will be transmitted over the lines.

As a result of this, the negative signal commenced at 276 (Fig. 5) in the manner above explained, will continue until the system is prepared to send out a positive signal over the lines 146 as will be explained presently. However, before passing on to the next cycle of operation of the system, it should be pointed out that the flow of current through the coil 272, in the manner above explained, serves to shift the bank of relay armatures 123a, b, and c toward the left in Figs. 3a and 3b, thereby conditioning the system for the transmission of signals identified with figures rather than letters.

Now upon the completion of the cycle, i. e., half revolution of the shaft 127 identified with the figure shift designation on the control tape, let it be assumed, in accordance with Fig. 5, that the next character to be printed is the Figure 5. This will mean that during the half revolution of the shaft 127, the tape will have been shifted to a position in which an opening is provided in line with the feeler pin 112 and the feeler pins will have been released to permit the feeler pin 112 to pass through the opening. As the bump 172 on the printer shaft cam disc 131 shifts the arm 133 toward the left upon the completion of the figure shift cycle of the timing shaft 127, the pawl 109 will be retracted from the ratchet 108 in the manner previously set forth and the brush arms will be permitted to sweep across the commutator segments until the brush associated with the commutator 104 reaches the segment 278 identified with the character 5. At this point a circuit will be completed from the negative side 151 of the current source, through the relay armature 121, line 217, armature 120b, line 218, armature 119d, armature 118h, and armature 117p to the contact 279, which, it will be understood, is connected with the segment 278 of the commutator. From the latter the circuit is completed through the collector ring section 280 and the line 225, branch line 226, contact 227, armature 123a, and line 159 to the positive side 160 of the current source. In shifting from the segment 258 of the commutator 104 to the segment 278, the brush identified with commutator 102 will be carried over a series of the segments of this commutator to the segment 281 and then to the insulating space 282 just beyond segment 281. This, as indicated in Fig. 5, results in the transmission over the lines 146 of a series of positive and negative pulses concluding with a negative pulse 283 just prior to the open signal predetermined by the insulating section 282 of the commutator 102. As previously explained in connection with the transmission of the character W and the printing of the latter, a long open printing signal will be sent over the lines 146 at this time, the length of this being indicated by the section 294 of the current flow line of Fig. 5. As in the case of the transmission of the character W, the completion of the long open printing signal will be followed by a restoration of the negative signal over the lines 146, as indicated by the section 285 of the current flow line in Fig. 5.

Now assuming that the next character to be

printed is another figure 5, the new position of the tape will have an opening in the line with the feeler pin 112 so that the circuit through the fan bank will be restored immediately upon the release of the feeler pins by the magnet 150. Accordingly, as in the case of the figure shift signal, the pawl 109 will not be retracted upon the completion of the cycle of the print timing shaft 127 so that no shifting of the brush arms will take place. This, it will be understood, is due to the fact that the armature 169 will be drawn toward the left as soon as the circuit through the coil 194 is broken by the coaction of the bump 283 on the disc 132 with the arm 134. This will occur before a circuit could be completed from the negative side 171 of the current source, through the line 170, armature 169, line 168 and coil 166 to the positive side 167 of the current source. Accordingly, the effect of selecting the same character for printing again is simply to retract the detent pawl 128 and to permit another half revolution of the print timing shaft 127 with the various functions incident to its operation.

From time to time it is desirable to transmit a unison signal for the purpose of insuring that all of the outlying printers are in unison with the transmitter. This is set forth in some detail in the Ackell et al. Patent No. 2,017,087 above mentioned. Substantially the same arrangement may be provided in connection with the new control system. Briefly, the arrangement may be such that when the unison signal is to be sent out, the portion of the tape presented at the analyzer pins will have no holes therethrough so that the armatures of all the relays of the fan bank will be held toward the left. This will carry the current from the negative side 151 of the current source to the point 286 which is not connected with any segment on the commutator 104 and, therefore, the circuit through the fan bank cannot be completed. Accordingly, when the ratchet 108 is released upon the retraction of the pawl 109 at the completion of the preceding printing cycle of the shaft 127, the brush arms 105 and 106 will be permitted to rotate continuously until arrested by the special means disclosed in the above mentioned patent. This involves a worm and a follower which is permitted to travel along the worm unless and until it is shifted out of the latter, which occurs upon each release of the timing shaft 127. Therefore, in the ordinary operation of the system, the follower does not travel far enough to have an effect upon the system. However, when the unison signal is predetermined by the tape, the follower is permitted to travel until it brings about the actuation of a switch diagrammatically illustrated at 287 in Fig. 3a. When this switch is closed, a circuit from the source 151 is carried to the space segment 288 of the commutator 104 and the brush arm 106 will, therefore, be arrested when the associated brush reaches this segment during the subsequent revolution. This, in the preferred construction, will ordinarily be on the 5th revolution of the brush arms. The control of the printing operation then takes place in the same manner as if the spaced character had been expressly predetermined by the tape. It will be understood, however, that the selection of the space position of the printing wheels at the several printers will be brought about by the arrangement disclosed in the above mentioned Ackell and Paulding patent. Briefly, this may involve stopping the printing wheel shaft, by a positive stop finger or the like, in a predetermined

position in which the space portion of the wheel is opposite the platen, after the printing wheel has been permitted to rotate about three complete revolutions.

Provision is made for temporarily arresting the operation of the transmitter when the tape available for analysis by the analyzer 111 becomes less than a predetermined minimum, i. e., when it is being analyzed at a more rapid rate than it is being supplied from the punching machine or machines. For this purpose an arm (not shown), which cooperates with the tape at a point just in advance of that at which it is analyzed by the pins of the analyzer 111, is operated by the tape, when the latter becomes relatively taut, and is shifted to a position in which it opens a circuit at the point 289 in Fig. 3b. This serves to break the circuit which normally extends from the positive side 191 of a current source through the switch 289, line 293, and magnet coil 291 to the negative side 292 of the current source. Normally the current thus flowing serves to hold a detent arm or pawl 293 in the raised position indicated in Fig. 3b, out of the path of the projections 294 on a disc 295 secured to the print timing shaft 127. When the current is broken by the operation of the switch 289, as explained, the arm 293 is released and serves to arrest the disc 295 on the next print timing cycle of the shaft 127 in a position about 30° removed from the normal completion of the print timing cycle. This is such that the projection 298 on the cam 132 is in engagement with the arm 134, thus completing the circuit, hereinabove described, through the relay coil 218 and thereby serving to draw the armature 212 toward the left. This, as previously explained, completes a circuit from the negative side 207 of the power source through the armature 212, line 214, and coil 202 to the positive side 201 of the current source and insures the maintenance of the armature 149 in the closed circuit position indicated in Fig. 3b. Accordingly, during the period in which the transmitter is held out of operation by the engagement of pawl 293 with one of the lugs 294, the last signal sent out over the lines 146 will be sustained. When additional tape is supplied to the analyzer, the switch 289 is again closed and the pawl 293 is retracted to permit completion of the unfinished cycle of the print timing shaft 127. The operation of the system, which is thus resumed, is the same as if it had not been interrupted.

Provision is made for transmitting over the lines 146 a relatively long open signal which is substantially longer than the open signal which brings about the carriage return and may be in the neighborhood of 5 seconds. This is adapted for the ringing of a bell at each of the printers connected with the lines 146. When such a bell signal is to be transmitted a figure shift must first take place, in the manner hereinabove described, and this is then followed by a series of holes in the tape corresponding with the letter S, these holes being aligned with the pins 114 and 116. It should be borne in mind that the feeding of the tape and the release of the feeler pins to cooperate with the new openings in the tape occurs during an early portion of the cycle of the print timing shaft 127 identified with the preceding character determined by the tape. This preceding signal may have been associated with a figure, or with the figure shift if letters were being transmitted immediately prior to the bell ringing signal. Immediately upon the new

positioning of the pins of the analyzer, a circuit will be completed through the fan bank without movement of the brush arms 105 and 106, i. e., this circuit is completed regardless of the position of the brush arms. It may be traced as follows: from the negative side 151 of the power source, through the coil 152, armature 121, line 153, armature 120a, armature 119b, armature 118c, and armature 117f, to the contact 231. From this contact the circuit continues through line 230, coil 229, coil 228, line 226, contact 227, thence through the relay armature 123a, which will have been shifted toward the left by the figure shift signal, and then through line 159 to the positive side 160 of the current source. Completion of the circuit in this manner through the coil 229 will draw the armature 204 toward the right and thus open the circuit from the negative side 207 of the current source, through armature 206, line 205, etc. to the positive side 291 of the current source. At this time the parallel circuit connecting the points 201 and 207 through the lines 214 and 212 and armature 212 will be closed. However, this parallel circuit will be opened upon the completion of the preceding cycle of the print timing shaft 127, because of the swinging of the arm 133 to the left and the completion of a circuit from the negative side 171 of the current source through line 170, armature 169, line 241, armature 242 (which will be in its lefthand position), line 243, and coil 244 to the positive side 245 of the current source. In thus energizing the coil 244, the armature 212 will be swung toward the right to open the parallel circuit mentioned. This will result in the release of the armature 149 by the coil 202 and will initiate an open signal which will be transmitted over the lines 146.

It should be noted at this point that the circuit, which is normally completed upon the shifting of the arm 133 toward the left, on the completion of a circuit through the fan bank, to bring about the retraction of the detent pawl 128 of the print timing mechanism, will be broken so that the print timing shaft 127 will not be released. This is due to the passage of the current, as explained above, through the coil 229 which causes armature 121 to be shifted toward the right. It will be recalled that the circuit which normally brings about operation of the pawl 128 extends from the negative side 171 of the current source through line 170, armature 169, line 173, line 174, armature 175, lines 176 and 177, coils 178 and 179, line 180, and armature 181 to the positive side 182 of the current source. Breaking of this circuit by the shifting of armature 121 toward the right also prevents energization of the coil 179 and, therefore, leaves the armature 183 toward the right, as it was last shifted, and thus prevents operation of the magnet 150 to retract the analyzer pins. Shifting of the armature 121 toward the right establishes a new circuit from the positive side 182 of the current source through a line 296 and a heater coil 297 to the negative side 298 of the current source. Coil 297 is associated with a thermal switch 299 of any suitable construction adapted to be operated when bi-metallic elements or the like are raised to a predetermined temperature. For the present purposes the construction is preferably such that it will require about 3 seconds of the passage of the current through the heating coil 297 to bring about the operation of the switch. When the switch is finally operated, contact is made between the point 303 on

the shiftable switch element with a stationary contact 301, thus completing a circuit from the positive side 302 of the current source, through a line 303 into line 180, to and through the coils 179 and 178, lines 177, 176, 174 and 173, armature 169, line 170, and arm 133 to the negative side 171 of the current source. Normal operation of the system is now restored again. It will be understood that the completion of the circuit just described will bring about the retraction of the pawl 128 and a cycle of operation of the print timing shaft 127 with its attendant functions, due to the action of coil 178 on the armature 183.

When it is desired to discontinue the transmission of signals, it is simply necessary to open the circuit through the lines 147 and 148 in any suitable manner, as by discontinuance of the current source. The prolonged open signal thus sent out over the lines 146 may, in a predetermined time of about 3 seconds, bring about a bell ringing operation at the printers, as above explained, and the discontinuance of the power for a substantial period of time beyond this will automatically shut-off the distant printers in the manner to be described in relation to a suitable printer per se.

Fig. 6 illustrates diagrammatically the circuits in a suitable form of printer which may be connected into one of the lines 146 of Fig. 3b for control by the transmitter of this embodiment. The means for controlling the printing wheel and the like by these circuits may be like that disclosed in Fig. 1. The signals coming in over line 146 to the printer may be passed through a rectifier 304, then through a coil 305, a line 306, the coil of a polarized relay 307 back to the opposite side of the line 146. Assuming that the signal thus received was a positive one, it would flow through the side 311 of the rectifier, thence through the coil 305, then the opposite side 310, of the rectifier, and through the balance of the circuit explained. A negative signal will pass from the opposite side of the line 146 to the coil 307 in the opposite direction, then the line 306, then the side 309 of the rectifier, then the coil 305 in the same direction as before, then the side 308 of the rectifier, back to the opposite side of the line 146. The passage of current through coil 305 in the manner indicated will draw an armature 312 toward the right, against the action of a spring, thereby completing a circuit from the positive side 313 of a current source through a line 314, to and through a heating coil 315 associated with a thermal starting switch, thence through a line 316 and then in parallel through print magnet coils 317, as one branch, and shift magnet coil 318, as the other branch, to and through a line 319 to the negative side 320 of the current source. Within a few seconds the current thus passing through the heating coil 315 will cause the thermal switch 321 to close and thus complete a circuit from the positive side 313 of the current source, through a branch 322 and a line 323 to a line 324, thence to and through a motor 325 and also, in parallel therewith, through a voltage divider 326, 327, to and through a line 328 and a further line 329, to and through the thermal switch 321 to the negative side 320 of the current source.

The alternate positive and negative pulses received over the line 146 passing in opposite directions through the polarized relay coil 307 will cause the armature 330 of the latter to shift

alternately from one side to the other. When it is shifted to the lefthand position, indicated in Fig. 6, current will flow from the positive side 313 of the current source through lines 322, 323, and 324 and thence through section 327 of the voltage divider to and through a line 331 to a coil 332 of the escapement magnet, which corresponds with the coil 26 of Fig. 1, thence back through a line 333, armature 330, a line 334, to line 329, thermal switch 321, etc. back to the negative side of the current source. When the armature 330 is shifted toward the right, current will flow from the positive side 313 of the current source through lines 322, 323, and 335 to and through the armature 330, thence through a line 336 and line 333 to and through the escapement magnet coil 332, in the opposite direction from the previous direction of flow, then through line 331, section 326 of the voltage divider, and lines 328 and 329, back to the thermal switch 321 and the negative side 320 of the current source. In this manner it will be seen that the escapement pawl of the selecting mechanism will be rocked alternately to one side and then another to permit the printing wheel to be shifted step by step to a new setting in the same manner as explained in connection with Fig. 1. It should be noted, however, that coil 332 has current flowing through it at all times, in one direction or the other, thereby insuring that the pawl will be held to one side or the other.

Now when an open signal is transmitted over the line 146 it will be apparent that since no current will flow through coil 307, the armature 330 will be left in its last position, moreover no current will flow through the coil 305. The armature 312 will, accordingly, shift toward the left. Relay 305 may be a fast relay which responds immediately to an open signal, thus speeding up the printing operation over that of existing machines. This opens the circuit previously described from the positive side 313 of the power source through line 304, heating coil 315 and line 316 to and through the print and shift magnets 317 and 318 back to the negative side of the current source. As in the case of the Fig. 1 arrangement, if the open signal thus transmitted is of short duration, printing will take place without a backward shifting of the printing wheel, whereas if the open signal is of longer duration the magnet 318 will be disabled during the operation of the push back pawl (corresponding with the pawl 49 of Fig. 1) and will thus bring about a backward step of the printing wheel prior to the operation of the printing platen.

When it is necessary to effect the return of the carriage of the printer and advance the paper to a new line, the type wheel mounted on the carriage will be rotated, as hereinabove explained, to a position identified with the carriage return function. The step by step rotation of the type wheel will carry it to a position one space beyond the carriage return position and during the ensuing printing operation the wheel will be turned backwardly this one step to position the carriage return space on the type wheel in line with the platen. This position on the type wheel is preferably left blank so that no character will be printed. Means of any suitable character may be employed within the printer to bring about the return of the carriage at this time. Typical examples of suitable carriage return mechanisms may be found in Landfeare Patent No. 765,978, granted July 26, 1904, and in Cenger Patent No. 1,178,215, granted April 4, 1916. In both of these

constructions it will be noted that the step-by-step advance of the carriage across the paper is effected by means of a pair of ratchet toothed racks cooperating with a pair of pawls mounted on the carriage. When the type wheel is positioned in its carriage return position during a printing operation, suitable means is made effective to lift the pawls from the racks and to maintain them out of engagement with the racks for a sufficient period of time to enable a spring to restore the carriage toward the left side of the sheet on which the printing is taking place. In the arrangement disclosed in the Landfear patent, the lifting of the pawls in the manner explained is accomplished mechanically, whereas in the arrangement disclosed in the Conger patent, it is accomplished electrically by the energizing of a suitable magnet. In either case the means for lifting the pawls is under the control of a pin or projection carried by the printing wheel supporting shaft and which is brought in line with the end of a lever or other member when the printing wheel is in its carriage return position. It should be noted in this connection that the duration of the open signal associated with the return of the carriage is of sufficient length to allow for the return of the carriage by the spring, in the manner explained, before a new set of pulsing signals is transmitted to the printer. The feeding of the paper to the next line may be accomplished in the manner disclosed in either of the patents mentioned above and will occur simultaneously with the return of the carriage toward the left. Substantially the same amount of time is required for these two operations.

The means in the printer for responding to a unison signal sent out by the transmitter, in the manner hereinabove explained, may suitably be of the type disclosed schematically in the Paulding Patent No. 1,957,076, granted May 1, 1934. Briefly, it may involve a worm on the printing wheel supporting shaft arranged to cooperate with a finger which is advanced along the worm so long as it is in engagement with the worm and until it strikes a fixed abutment on the worm. When this abutment is reached further turning of the worm is prevented and the printing wheel supporting shaft will come to rest in a definite position, preferably corresponding with the space position of the printing wheel. The friction clutch through which the shaft is driven will then simply slip. In the normal operation of the printer, when a succession of characters are being printed, the finger which rides in the worm in the manner above explained is disengaged from the worm upon each operation of the printing shaft of the printer and it is thus permitted to be returned by a spring to its initial position prior to the commencement of the succeeding selecting operation. The means for lifting the finger out of engagement with the worm may be associated with the longitudinally movable rack in a printer of the type disclosed in the Paulding patent, or in the Landfear and Conger patents, or it may be operated by a cam, such as the cam 64 in Fig. 1, carried by the printer shaft of the printer.

Let us turn now to the operation of the bell in the printer, in response to the transmission of a bell ringing signal. As above explained in connection with the transmission of this signal, it must be preceded by a figure shift signal within the transmitter and it must also be preceded by the transmission of a character of a particular type. This type must be such that it will have

left the armature 330, controlled by the coil 307 of the polarized relay, toward the left, as shown in Fig. 6. To insure this the operator who controls the transmitter will be instructed to precede a bell ringing signal by the transmission of a particular character, such as a space. Now when the long open signal identified with a bell ringing operation is transmitted over the lines 146, the armature 312 will be shifted toward the left and a circuit will, therefore, be completed from the positive side 313 of the current source through armature 312, a line 337, a heating coil 338, a line 339, line 336, armature 330, lines 334 and 329, thermal switch 321, and a line 340, back to the negative side 320 of the current source. This circuit will remain closed throughout the long open signal predetermined by the thermal switch 299 of the transmitter (Fig. 3b). During this time interval the heating coil 338 will heat up a thermal switch 341, of any suitable bimetallic construction, and close a circuit through a bell 342. This circuit extends from the positive side 313 of the current source, through line 322, a line 343, switch 341, bell 342, and a line 344, back to the negative side 320 of the current source. Upon completion of the long-open bell ringing signal, the current through the heating coil 338 will be discontinued and the thermal switch 341 will be opened to stop the ringing of the bell. The bell may, however, be of a single stroke type which will be sounded only once, regardless of the duration of the flow of current through the bell circuit.

It should be noted in connection with the foregoing that the circuit through the heating coil 338, described above, will be completed during each printing operation in which the armature 330 is toward the left, as shown in Fig. 6, but the duration of the printing operation is not long enough to cause heating of the thermal switch 341 to the extent necessary to close the bell ringing circuit.

When it is desired to discontinue the operation of the printer, the circuit formed in part by the line 146, will be left open for an exceptionally long period, as has been explained above. This period, of say 4 or 5 minutes' duration, will bring about the cooling of the thermal switch 321 sufficiently to open the circuit closed initially by the heating of the coil 315. This will place the printer out of operation. It should be noted in this connection that if the armature 330 is toward the left at the time this long-open signal is received, it will bring about the operation of the thermal switch 341, and the ringing of the bell 342, before the thermal switch 321 cools sufficiently to stop the printer. This ringing of the bell is ordinarily considered desirable and, therefore, prior to concluding the operation of the transmitter a signal is preferably sent out which will insure leaving the armatures 330 of the various printers toward the left.

The operation of the system has been explained in such detail in connection with the description of the various parts that no résumé is believed to be necessary. It will be understood that, while several illustrative transmitters and printers, and their circuits, embodying features of the invention have been disclosed in considerable detail, numerous changes or variations, in addition to those specifically mentioned, may be made without departing from the general principles and scope of the invention.

We claim:

1. In a telegraphic printing system, means for

transmitting positive, negative, and open signals in accordance with a desired message, said means including devices adapted to transmit open signals of different duration, a printer comprising a character printing wheel, means for turning said wheel step-by-step to select groups of characters, auxiliary means for turning said wheel after the selection of said group to select a particular character within said group, means for effecting a printing operation from the particularly selected character, and control means responsive to said positive and negative signals for controlling said step-by-step turning means and responsive to said open signals in accordance with the duration thereof for controlling said auxiliary means and said means for effecting a printing operation.

2. In a telegraphic printing system, means for transmitting positive, negative, and open signals in accordance with a desired message, said means including devices adapted to transmit open signals of different duration, a printer comprising a character printing wheel, means for turning said wheel step-by-step to select groups of characters, auxiliary means for turning said wheel after the selection of said group to select a particular character within said group, means for effecting a printing operation from the particularly selected character, and control means responsive to said positive and negative signals for controlling said step-by-step turning means and responsive to said open signals depending upon the duration thereof for controlling said auxiliary means and said means for effecting a printing operation, said control means including devices for determining the operation or the non-operation of said auxiliary turning means selectively in accordance with the duration of the open signal.

3. In a telegraphic printing system, means for selectively determining and transmitting positive, negative and open signals over a single circuit to a distant point, said means including devices for transmitting effective open signals of different duration, a printing wheel, means for rotating said wheel, means responsive to the positive and negative signals for controlling the step-by-step rotation of said printing wheel, means for taking printing impressions from said wheel, means including a rectifier and a relay responsive to open signals of predetermined duration for causing the operation of said impression taking means, and means responsive to an open signal of different duration for disabling said wheel rotating means.

4. In a telegraphic printing system, means for selectively determining and transmitting positive, negative and open signals over a single circuit to a distant point, said means including devices for transmitting open signals of different duration, a printing wheel, means for rotating said wheel, means responsive to the positive and negative signals for controlling the step-by-step rotation of said printing wheel, means for taking printing impressions from said wheel, and means including a rectifier and a relay in said single circuit and a plurality of magnets connected with said rectifier and relay and responsive to open signals of different duration for controlling the operation of said impression taking means to selectively effect printing impressions from different portions of said wheel as positioned by said step-by-step rotation.

5. In a telegraphic printing system, means for selectively determining and transmitting positive, negative, and open signals over a single circuit to a distant point, said means including devices

for transmitting open signals of different duration, a printing wheel, means for rotating said wheel, means responsive to the positive and negative signals for controlling the step-by-step rotation of said printing wheel, auxiliary means for turning said wheel a portion of a step, means for taking printing impressions from said wheel, means for operating said impression taking means, magnets for controlling the operation of said auxiliary means and said operating means, and means including a rectifier and a relay responsive to open signals of different predetermined durations for selectively causing said magnets to be energized.

6. In a telegraphic printing system, means for selectively determining and transmitting positive, negative, and open signals over a single circuit to a distant point, said means including devices for transmitting open signals of different duration, a printing wheel, means for rotating said wheel, means responsive to the positive and negative signals for controlling the step-by-step rotation of said printing wheel, auxiliary means for turning said wheel a portion of a step, means for taking printing impressions from said wheel, means for operating said impression taking means, magnets for controlling the operation of said auxiliary means and said operating means, and means including a rectifier and a relay responsive to open signals of different predetermined durations for selectively causing said magnets to be energized, the construction and arrangement being such that said auxiliary means is rendered effective only upon an open signal of relatively long duration.

7. In a telegraphic printing system, means for selectively determining and transmitting positive, negative and open signals over a single circuit to a distant point, said means normally producing open signals of a given duration but including a relay and a condenser in circuit therewith for predetermining an open signal of a longer duration, a printing wheel, means for rotating said wheel, means responsive to the positive and negative signals for controlling the step-by-step rotation of said printing wheel, means for taking printing impressions from said wheel, means responsive to open signals of different predetermined duration for causing the operation of said impression taking means, and auxiliary means operable in response to open signals of one of said durations for causing a part step movement of said wheel as a preliminary to the operation of said impression taking means.

8. In a telegraphic printing system an electrical current source, conducting means connected with said current source for transmitting signals to a distant printer, commutator means associated with said current source for predetermining positive, negative and open signals, punched tape controlled means variously connected with the segments of said commutator means for controlling the operation of said commutator means, and means comprising a rectifier and a relay connected with said conducting means for distinguishing between an open signal and a temporary interruption of current between positive and negative signals.

9. In a telegraphic printing system, means including a commutator and a plurality of electrical circuits for transmitting signals, a printing wheel having a plurality of characters around its periphery to be printed, and means responsive to said signals for controlling the rotation of said wheel to the successively desired positions for

printing, said commutator having a segment identified with each of said characters on the wheel, the segments identified with alternate characters on said wheel being arranged in the same sequence as said characters, and the segments identified with the intermediate characters on said wheel being arranged two steps in advance of the corresponding characters on the wheel in relation to the first series of segments and characters.

10. A telegraphic printing system comprising a transmitter having means to send out positive, negative, and open signals over a single circuit, and a printer responsive to all of said signals for recording transmitted messages, said printer having a thermal switch responsive to the flow of current involved in any substantially continuous series of positive and negative signals in said circuit for setting the printer into operation and responsive to the cessation of said current flow for a predetermined time interval for throwing said printer out of operation.

11. A telegraphic printing system comprising a transmitter having means to send out current and no current signals over a single circuit, and a printer responsive to all of said signals for recording transmitted messages, said printer having a thermal switch responsive to the flow of current involved in any succession of current signals in said circuit for setting the printer into operation and responsive to the cessation of said current flow for a predetermined time interval for throwing said printer out of operation.

12. A telegraphic printing system comprising a

transmitter having means to send out positive, negative, and open signals over a single circuit, said means including devices adapted to predetermine open signals of different duration, and a printer responsive to said signals, said printer having means responsive to open signals of different duration for performing a plurality of different functions, said responsive means including devices adapted to effect a printing operation upon certain of said open signals and to attract attention upon other of said open signals and to discontinue the operation of said printer upon receipt of an open signal of extra long duration.
